UNITED STATES PATENT OFFICE.

JOHN J. PARKINSON, OF CHICAGO, ILLINOIS.

HOT-WATER SYSTEM.

Application filed August 11, 1924. Serial No. 731,400.

To all whom it may concern:

Be it known that I, JOHN J. PARKINSON, a citizen of the United States, and a resident of Chicago, county of Cook, and State of Illinois, have invented a new and useful Improvement in Hot-Water Systems, of which the following is a full, clear, and exact description.

My invention relates to improvements in hot water systems, and it consists in the combinations, constructions, and arrangements herein described and claimed.

An object of my invention is to provide an improvement over that form of the device shown in my co-pending application, Serial No. 656,516, filed August 9, 1923. In my co-pending application I showed a hot water system which made use of a pipe that was disposed in the water in the boiler of the furnace and which also made use of a reserve tank, this reserve tank holding the water so as to be ready for instant use when desired. The principal object of the present invention is to provide a hot water system in which the piping in the house itself acts as a reservoir for the hot water and therefore does away with the customary reservoir tank.

A further object of my invention is to provide a device of the type described in which the hot water is kept circulating throughout the entire piping system of the house, whereby hot water may be obtained from any of the faucets in the house the instant the faucet is turned on.

A further object of my invention is to provide a tankless hot water system of the type described in which the hot water is retained in the piping system in the house, thereby conserving the heat which is ordinarily lost by radiation when a large storage tank is used, and also doing away with the inconvenience of cleaning the storage tank from time to time.

A further object of my invention is to provide a hot water system of the type described in which hot water may be instantly obtained as soon as the faucet is turned on, thereby eliminating the waste of water which is caused when a large quantity of cold water is run off in the systems now in use in order to obtain hot water.

Still another object of my invention resides in the provision of means for preheating the incoming cold water by means of the water heated in the system so as to permit

the introduction of the cold water directly into the partitioned tubes at the hottest part of the boiler.

A further feature of my invention resides in the construction and arrangement of the sheet metal partition for the liquid heating members.

A further object of my invention is to provide a hot water system of the type described which has novel means for cleaning the system of any foreign matter.

Other objects and advantages will appear in the following specification, and the novel features of the invention will appear in the appended claims.

My invention is illustrated in the accompanying drawings, forming part of this application, in which

Figure 1 is a side elevation of the device as shown operatively applied to a boiler,

Figure 2 is a front elevation of the device,

Figure 3 is a section along the line 3—3 of Figure 2, and

Figure 4 is a section along the line 4—4 of Figure 3.

Figure 5 is a section through one of the headers showing the partition therein and also the partition in the tube.

In carrying out my invention I make use of a boiler 1 which is provided with a customary fire door 2 and draft door 3. The boiler 1 is provided with a hot water tank 4, this water being used for the steam radiators and other like devices which are employed in the average house.

In Figure 3 I have clearly shown how the boiler 1 is provided with openings 5 through which pipes 6 are disposed. These types of tubes 6 form water conducting and heating elements. They are closed at their rear ends and are provided at their forward ends with threads adapted to screw into headers, the construction of which is shown in figure 5 of the drawings. Each of these headers is provided with an inlet opening to which connects the pipe 7 and each is provided with an outlet or discharge opening which also connects pipe 7, the former pipe of the first header of the series is the cold water inlet while the latter pipe 7 of the last header of the series is the hot water discharge. The heater is also provided with a front opening closed by a screw plug 7*. The rear of the header is provided with an opening preferably opposite the opening closed by the plug 7*. This is the opening in which

the tube 6 threads. In addition, the header is provided with a partition 7² which extends entirely across the header so as to separate the inlet opening from the discharge opening. Each tube 6 is provided with a detachable partition adapted to cause the water to traverse the tube in a plurality of directions. In the preferred form of my invention this partition is a single piece 10 of sheet metal which is folded longitudinal- 70 ly of the tube whereby to provide the intermediate strengthening rib or fin 8^y and the two lateral flanges 8' which extend in diametrically opposed directions whereby 15 preferably to sub-divide the tube 6. And preferably the projecting ends of these flanges are provided with skirts 8^x which engage the inner walls of the tube as shown clearly in Figure 4. It will be noted that by 20 forming the partition member as above described, the strengthening rib and the lateral flanges form resilient members which engage and grip the inner walls of the tube and thereby hold the partition in place. And 25 due to this construction the hot water causes these flanges and the skirts 8^x to expand and effect a substantially water tight joint with the inner walls of the tube. And this construction also permits the quick detachability 30 of the partition if it be desired to clean out the tube. The partition is inserted in the tube with the flanges 8 in the plane of the header partition 7², thereby forming a lower water channel which communicates 35 with the inlet opening of the header and upper water channels communicating with the outlet of the header.

It will be noted that the headers disclosed in Figures 2 and 3 of the drawings are all 40 connected in series so that the discharge of one header will connect the water into the inlet opening of the next header and so on throughout the series. In this way the water is compelled to travel in reverse directions 45 successively throughout all of the headers so that by the time it reaches the last header it is heated to the desired temperature. These pipes are connected to a common pipe 7 and are provided with partitions 8'. It 50 will be noted from Figure 3 that the partitions 8' are arranged so as to cause the water flowing through the pipe 7 to pass through all of the pipes 6. The arrows show the course of the water as it flows through 55 the various pipes. The pipes 6 extend into the hot water in the compartment 4 and it will therefore be seen that the water within the pipe 6 will be heated and will therefore pass on through the pipe 8 to a heat equal- 60 izer or preheater 9. In Figure 3 only one plug 7^x is shown. It is to be understood that all of the headers are provided with front openings closed by similar plugs.

The equalizer or preheater for the cold 65 water 9 is in reality a large cylinder which

has a partition 10 therein that divides the cylinder into an upper compartment 11 and a lower compartment 12. The pipe 8 communicates with the compartment 11 while the pipe 7 communicates with the compartment 12. A cold water inlet pipe 13 also 70 communicates with the compartment 12. The water flows through the pipe 13, the compartment 12, the pipe 7, and to the pipes 6. The water flowing from the pipe 13 to 75 the pipe 7 comes in contact with the partition 10 and is warmed to a slight extent by the conduction of heat which is given off by the heated water passing through the compartment 11. By means of this preheating 80 the cold water, which in winter is often below forty degrees Fahrenheit, may be introduced directly into the partitioned tubes without danger. These tubes are located just above the crown sheet of the fire box 85 and submerged in the boiler water. This is the zone of maximum temperature within the boiler. The water from the compartment 11 is conveyed by means of a pipe 14 to the hot water system in the house, (not 90 shown). A return pipe 15 is also connected to the hot water system and communicates with the pipe 7. A check valve 16 is disposed in the pipe 15 and permits the water 95 to flow in the direction of the arrow through the pipe 15 but prevents the water from flowing in a reverse direction.

From the foregoing description of the various parts of the hot water system, the operation thereof may be readily understood. It will be seen that the pipe 7, pipes 6, the pipe 8, the compartment 11, the pipe 14, and the pipe 15 provide a continuous route for the flow of water throughout the entire hot water system of the house. As 100 heretofore stated, the check valve 16 permits the water to flow in only one direction throughout this entire system. As long as there is hot water in the reservoir 4, there will be a flow of water through the hot water 110 system in the house. It will therefore be apparent that the water will be hot at all points throughout the hot water system and that hot water will be obtained the instant any one of the faucets is turned on. 115

In Figure 1 I have shown two discharge pipes 17 and 18 which communicate with the pipe 7. A valve 19 is disposed between the pipes 17 and 18 and may be opened and closed at the will of the operator. The 120 valves 20 and 21 are disposed in the pipes 17 and 18 and are normally closed. The valves 19, 20, and 21 are for the purpose of cleaning the system of any foreign matter that may become lodged therein. When the 125 valve 20 is opened and the valves 19 and 21 closed the water will flow through the pipe 14, the compartment 11, the pipe 8, the pipes 6, the pipe 7 in a direction reverse to the normal flow, and out through the pipe 17. 130

The weight of the column of water in the hot water system in the house will cause this flow. The water as it flows in this direction will clean out all of the foreign matter in the piping system. If now the valves 19 and 20 are closed and the valve 21 opened, the water will flow through the pipe 13, the compartment 12, and also through the pipe 15 and through the portion of the pipe 7 that extends between the compartment 12 and the pipe 18. When these two valves are closed, i. e., the valves 19 and 20 and the valve 21 is opened, the flow of the water will clean the hot water system of the foreign matter in that portion of the system that connects with the pipe 15 and also out of the compartment 12 that connects with the cold water supply pipe 13. It will therefore be seen that the entire system may be cleaned by either causing the water to flow through the pipe 17 or the pipe 18.

As heretofore stated I have provided two novel advantages by substituting the hot water system in the house for the storage of hot water in place of the customary storage tank. The first and principal advantage lies in the fact that the person who wishes to use hot water is assured of getting hot water the instant he turns on the faucet. This is due to the fact that the hot water is kept circulating throughout the entire hot water system as long as there is any hot water in the boiler 1. The second advantage lies in the fact that the storage tank is eliminated and therefore reduces the expense of such a tank and also cuts down the amount of radiation which is usually given off by a large tank. Another important point to consider is the point that the cleaning of the storage tank is also done away with. The device is simple in construction and may be readily installed in almost any type of standard boiler.

I claim:

1. The combination with a boiler and a hot water system, an equalizer having a partition therein dividing the equalizer into two compartments, a cold water pipe in communication with one of said compartments, an outlet pipe leading from said compartment, a plurality of pipes having partitions therein, said pipes adapted to be disposed in the water in said boiler, said outlet pipe being connected to said pipes having the partitions therein, a pipe in communication with said partition, pipes, and with the other compartment, a pipe connecting said last-named compartment with the hot water system, and another pipe connecting the hot water system with said outlet pipe, and discharge pipes in communication with said outlet pipe for cleaning the partitioned pipes, compartments, and hot water system from foreign matter.

2. A tankless water heating system for

buildings and the like comprising in combination with the boiler of a hot water heater, piping forming a closed water-circulating system for the building, said piping having in series therein a plurality of water conducting and heating members disposed in the water of the boiler, each member being partitioned to cause the water to flow in a plurality of connected paths therein and said members being connected in series to cause each one to discharge into the succeeding member, a cold water supply for said system, a water drain and means associated therewith for reversing the flow of water through said partitioned members to clean the same.

3. A tankless water heating system for buildings and the like comprising in combination with the boiler of a hot water heater, piping forming a closed water-circulating system for the building, said piping having included in series therein a plurality of water conducting and heating members disposed in the water of the boiler, each member being partitioned to divide the member so as to compel the water to traverse the member in a plurality of directions, said members being connected in series in said piping circuit to cause the water discharging from one partitioned member to enter the next partitioned member whereby a continuous supply of hot water is constantly circulated in said system.

4. A tankless water heating system for a building or the like, comprising in combination with the boiler of a hot water heater, a plurality of partitioned members projecting into the water in said boiler and connected in series to cause the water to flow in series through said members and through each partitioned member in a plurality of directions, a hot water piping system for the building having the series of partitioned members connected in series in said system, a source of cold water supply and means for causing the incoming cold water to be pre-heated by the hot water of the circulatory system, and means for introducing said pre-heated water into the series of partitioned members.

5. A tankless water heating system for a building or the like, comprising in combination with the boiler of a hot water heater, a plurality of tubes projecting into the water in said boiler, partitions in said tubes for causing water to flow in a plurality of connected water heating paths in each tube, means for connecting said partitioned tubes in series whereby the water heated in one discharges into the next succeeding tube, a hot water pipe system for the building and having said partitioned tubes connected in series therein, a cold water preheater formed with a heat conducting partition adapted to provide separate hot and cold

water channels, said hot water channel being connected to the discharge from said partitioned tubes and to said system and said cold water channel being connected to 5 a source of cold water and to the inlet of said series of partitioned tubes.

6. A hot water heating device adapted to be inserted in the water of a hot water boiler comprising a header having an inlet 10 and a discharge and a rear opening, a partition in said header adapted to separate said inlet from said discharge, a tube detachably connected to said rear opening and closed at its rear end, and a single-piece 15 sheet metal partition disposed in said tube, said partition being folded centrally longitudinally to provide a strengthening rib and resilient lateral arms adapted to grip the side walls of the tube, said lateral arms 20 forming with said header partition separate water passages communicating at the rear of the tube.

7. A sheet metal partition for a liquid heating tube comprising a single piece of 25 sheet metal folded longitudinally to provide a strengthening rib and lateral flanges, the latter being provided with angularly disposed skirts adapted to engage the inner walls of the tube.

30 8. A sheet metal partition for a liquid heating tube comprising a main partition member adapted to extend longitudinally of the tube and having portions adapted to grip substantially diametrically opposed

portions of the tube walls, said member having a strengthening fin or rib extending laterally therefrom. 35

9. A partition for a liquid heater tube comprising a main partition member adapted to be inserted longitudinally of said tube 40 and to engage substantially diametrically opposed portions thereof, said member having a laterally extending strengthening rib adapted to engage an intermediate portion of said tube wall. 45

10. A tankless water heating system for buildings and the like, comprising in combination with the boiler of a hot water heater, piping forming a closed water circulating system, said piping having included 50 in series therein a hot water tap and a plurality of water conducting and heating members, said heating members being disposed in the water of the boiler, each member being partitioned to divide the member 55 so as to compel the water to traverse said member in a plurality of directions, said system being devoid of a water storing tank and being arranged to permit the constant circulation of hot water in the system. 60

11. A sheet metal partition for a liquid heating tube comprising a single piece of sheet metal folded longitudinally to provide a strengthening rib and lateral flanges, 65 said flanges being constructed and arranged to engage the inner walls of the tube in a substantially tight manner.

JOHN J. PARKINSON.
